UNITED STATES PATENT OFFICE.

CHARLES E. FANNING, OF MOLINE, ILLINOIS, ASSIGNOR TO GEORGE H. MCKINLEY, OF SAME PLACE.

PERAMBULATOR.

SPECIFICATION forming part of Letters Patent No. 651,624, dated June 12, 1900.

Application filed April 19, 1900. Serial No. 13,410. (No model.)

To all whom it may concern:

Be it known that I, CHARLES E. FANNING, a citizen of the United States, residing at Moline, in the county of Rock Island and State 5 of Illinois, have invented new and useful Improvements in Perambulators, of which the following is a specification.

This invention relates to folding perambulators, and particularly to that style known 10 as "go-carts."

The object of this invention is to construct a carriage of this character which can easily and quickly be folded into a very compact and convenient form for storing away, carrying 15 on street-cars, &c., and that will be light, strong, and durable.

The invention further consists in the construction and arrangement of the various parts, as will hereinafter be more fully de- 20 scribed and claimed.

Reference being had to the accompanying drawings, Figure 1 is a perspective view of a perambulator embodying my invention, the parts being shown as when in use. Fig. 2 is 25 a side elevation of the same, showing the parts in dotted lines in the positions they would assume when folded up. Fig. 3 is a front end elevation of the same. Fig. 4 is a fragmentary vertical longitudinal section of the same. 30 Fig. 5 is a detail perspective view of the trip-rod and trip for lowering the sides of the carriage. Fig. 6 is a detail perspective view of the locking-joint for holding the handle-bars in a raised position, and Fig. 7 is a vertical 35 section of the same.

Like parts are designated by like characters in the drawings.

1 denotes the front seat-supporting frame; 2, the rear seat-supporting frame.

40 3 denotes the seat.

4 denotes the back; 5, the sides.

6 denotes the front wheels, and 7 the rear wheels.

8 denotes the handle-bars, and 8' denotes 45 the handle.

9 denotes the foot-rest, and 10 denotes the extension-bottom.

The front seat-supporting frame 1 consists 50 of the vertical standards 12, connected near their lower ends by the cross-rod 13. The standards 12 are provided on their lower ex-

tremities with the inwardly-projecting upturned ends 12', connected to the cross-rod 13 and having formed on the said upturned portions bearings on which are mounted the 55 beveled gear-wheels 14, to which are rigidly connected the front axle-arms 6', carrying the front wheels 6.

15 denotes short vertical arms or hangers depending from the rod 13, in the lower ends 60 of which is mounted a cross-rod 16, on the ends of which are fixed bevel gear-wheels 17, in mesh with the gear-wheels 14. The gear-wheels 17 are provided with short downwardly-projecting arms or lugs 17', which are 65 connected by the cross-rod 18.

The rear seat-supporting frame 2 consists of the vertical standards 19, connected near their lower ends by the cross-rod 20. The extreme lower ends of the standards 19 are 70 turned inwardly and upwardly, joining the cross-rod 20, and provided with bearings to receive the bevel gear-wheels 21, having rigidly connected thereto the short axle-arms 7', supporting the rear wheels 7. 75

22 denotes the short vertical arms or hangers depending from the cross-rod 20, in the lower ends of which is mounted a cross-rod 23, on the ends of which are fixed bevel gear-wheels 24 in mesh with the bevel-gears 21. 80 The gear-wheels 24 are provided with short downwardly-projecting arms or lugs 24', connected by the cross-rod 25, the construction just described being the same as that described in connection with the front wheels 85 and the purpose of which will hereinafter appear.

26 denotes a longitudinally-extending bar connecting the cross-rods 16 and 23 and through which also pass the rods 18 and 25. 90

The seat 3 consists of the rectangular frame hinged at its front edge to the upper ends of the standards 12 and pivoted at its rear corners to the short stud-shafts 27, which are fixed on the sliding collars 27', encircling the 95 rear standards 19 and resting upon springs 28, coiled around the standards 19, the springs 28 being supported by nuts or a shoulder fixed upon the standards 19. The bottom of the seat 3 may be formed of any suitable material. Supported to slide in brackets 3' 3', fixed beneath the seat, is a supplemental seat or 100

extension 10, which when it is desired may be drawn out from under the seat, thereby forming a sleeping-carriage.

The sides 5 consist of the radially-disposed rods 5^a, connected at their inner and outer ends by the arc-shaped metal strips 5^b and 5^c.

29 denotes angular brackets fixed on the sides of the seat-frame near the front edges thereof, to the vertical portion of which is pivoted the lower forward ends of the arc-shaped strips 5^c. 30 denotes similar angular brackets fixed on the sides of the seat-frame near the rear edge thereof and to which is pivoted the lower ends of the inner arc-shaped strips 15 5^b. The lower forward ends of the arc-shaped strips 5^c are provided with the inwardly-projecting curved fingers 5^d, which are engaged by the rearwardly-projecting ends of vertical rods 31, the said ends working through vertical slots formed in the perpendicular portion of the brackets 29. The rods 31 pass through guide-holes in the seat-frame and are pivotally connected at their lower ends to the rearwardly-extended arms of the foot-rest 25 frame 32, pivoted to the standards 12.

33 denotes forwardly-projecting lugs fixed to the upper portions of the rear standards 19 and having their outer ends connected by the vertical rods 34 34, which are engaged by 30 the curved fingers 5^e on the upper ends of the arc-shaped strips 5^c of the sides 5 to limit the outward movement of the said sides.

The back 4 consists of the upper and lower cross-rods 4^a and 4^b, having their ends fixed 35 in the standards 19 and being connected by any material which will form a suitable back-rest. The upper ends of the standards 19 are tubular and provided with short vertical slots 19^a for the accommodation of the lower ends 40 of the handle-bars 8, to the lower ends of which is hinged the extension 8'. When the handle-bars are in an open or operative position, the lower ends and hinged portion thereof are slipped down into the tubular ends of the 45 standards 19 to the limit of the vertical slot 19', in which position the hinged joints will be locked and the handle-bars rigidly supported. If, however, it is desired to fold the handle-bars, they are withdrawn from the tubular ends of the standards 19 until the hinge-joints are clear of the tubular standards, when 50 they can be folded down, this construction being clearly shown in Figs. 6 and 7 of the drawings.

55 To fold the carriage, the outer side of the foot-rest is raised, causing the rearwardly-projecting ends of the vertical bars 31 to engage the inwardly-projecting fingers 5^d of the sides 5, overbalancing the said sides, 60 which will cause them to fall inwardly upon the seat 3. A further upward pull upon the foot-rest will cause the seat and the forward supporting-frame and wheels to be raised and folded back against the back-supporting frame. In raising the forward framework the bevel-gears 17 and 24 will be caused 65 to rotate by reason of the rods 18 and 25, con-

nected to the lugs 17' and 24' of the gears 17 and 24, passing through the longitudinal bar 26 in advance of the axis of said gears, this 70 arrangement making the said rods and lugs eccentric to the axis of rotation of said gears and causing them to be rotated thereby. The gears 17 and 24 being in mesh with the gears 14 and 21 will cause them to rotate, carrying with them the axle-arms, thereby turning the wheels flat against the folded body of the carriage, as shown in dotted lines in Figs. 2 and 3. My carriage is now in a compact form for transportation or storage. To open 80 the carriage, all that is necessary is a downward pull on the seat and foot-rest, which will result in a reverse movement of the parts, the carriage being then in position for use.

Various changes in the form, proportion, 85 and the minor details of construction may be resorted to without departing from the principle or sacrificing any of the advantages of this invention.

Having thus described my invention, what 90 I claim as new therein, and desire to secure by Letters Patent, is—

1. In a perambulator of the class described, the combination of the rear supporting-frame and back, the front supporting-frame and 95 seat adapted to be folded up against said rear supporting-frame and back, the sides hinged to said seat and adapted to be automatically folded down upon and raised up from said seat, means for automatically raising and 100 lowering said sides, the front supporting-wheels and the rear supporting-wheels adapted to automatically fold inwardly at right angles to their plane of rotation, and means for automatically folding said front and rear 105 wheels when the perambulator is folded, substantially as set forth.

2. In a perambulator of the class described, the combination of the rear supporting-frame, consisting of the rear seat-supporting 110 standards rigidly connected near their lower ends by a cross-rod having formed on their extreme lower ends, inwardly-upturned bearings and connected at their upper portions by the upper and lower back bars between 115 which and the standards is placed the material forming the back; the front supporting-frame, consisting of the short, front seat-supporting standards, hinged at their upper ends to the seat-frame, and rigidly connected near 120 their lower ends by a cross-bar, and having formed on their extreme lower ends, inwardly-upturned bearings; the seat-frame and seat, hinged to the said forward supporting-standards and having a resilient hinged connection with the said rear supporting-standards, the said seat and the said forward frame being adapted to fold together and against said rear supporting-frame; sides, having hinged connection with said seat and adapted to be 125 automatically folded down against said seat when the same is folded up against the back, means for folding said sides and again raising them; the front and rear supporting-

wheels adapted to be automatically folded at right angles to their planes of rotation and means for automatically folding said wheels, substantially as set forth.

5 3. In a perambulator of the class described, the combination of the rear supporting-frame and back, the front supporting-frame and seat, adapted to be folded up against the said rear supporting-frame and back, the sides 10 hinged to said seat and adapted to be automatically folded down upon and raised up from said seat, means for automatically raising and lowering said sides, said means consisting of the vertical rods pivoted at their 15 lower ends to the inner ends of the sides of the foot-rest frame, which are pivoted near their inner ends to the front supporting-standards, the upper ends of the said vertical rods being bent at right angles and enclosing fingers projecting inwardly from said sides, the front supporting-wheels and the rear supporting-wheels adapted to automatically fold inwardly at right angles to their plane of rotation, and means for automatically 20 25 30 35 40 folding said front and rear wheels when the perambulator is folded, said means consisting of the transversely-disposed rods supported in hangers from a rigid portion of the front and rear supporting-frames, and provided on their ends with vertically-disposed beveled gear-wheels having offsets connected by similar transverse rods, the said rods being connected together by a longitudinally-disposed bar, the said vertical bevel gear-wheels being in mesh with horizontally-disposed beveled gear-wheels mounted on bearings in the front and rear supporting-frames and having rigidly attached thereto, short stud shafts or arms forming journals for the front and rear supporting-wheels, and where-

by when the perambulator is folded, the said vertically-disposed gears will be rotated which will in turn rotate the horizontal gears and thereby cause said journal-arms and wheels to be folded inwardly, substantially as set forth.

4. In a perambulator of the class described, the combination of the rear supporting-frame and back, the front supporting-frame and seat, adapted to be folded up against the said rear supporting-frame and back, the sides hinged to said seat and adapted to be automatically folded down upon and raised up from said seat, means for automatically raising and lowering said sides, the front supporting-wheels and the rear supporting-wheels adapted to automatically fold inwardly at right angles to their plane of rotation, and means for automatically folding said front and rear wheels when the perambulator is folded, an auxiliary seat or extension supported in hangers beneath the main seat and adapted to be slid back beneath said main seat when not in use; the handle-bars provided at their lower ends with a hinged extension and having a sliding engagement with the upper hollow slotted ends of the rear supporting-standards whereby said handle-bars may be withdrawn from said hollow ends of the standards far enough to clear 60 65 70 75 said hinged joint, when they can be folded down against said standards, substantially as set forth.

In testimony whereof I have hereunto set my hand in the presence of two subscribing witnesses.

CHARLES E. FANNING.
